UNITED STATES PATENT OFFICE.

LEWIS W. CHUBB, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTROLYTIC CONDENSER.

Application filed December 30, 1919. Serial No. 348,444.

To all whom it may concern:

Be it known that I, LEWIS W. CHUBB, a citizen of the United States, and a resident of Pittsburgh, in the county of Allegheny and State of Pennsylvania, have invented a new and useful Improvement in Electrolytic Condensers, of which the following is a specification.

My invention relates to electrolytic condensers and it has, for its primary object, the construction of condensers which shall provide satisfactory power-factor correction under continuous operating conditions.

It is well known to those familiar with the art that condensers, of the type formed by employing a plurality of film-forming plates immersed in a suitable electrolyte, connected in a power-supply circuit for power-factor correction, or for other purposes, tend to become unstable and operate with an increased power factor or with increased losses. This unstable condition obtains when the voltage impressed upon one of the electrodes is slightly higher than on the other, which causes the electrode having the higher impressed voltage to have less capacitance than the other. This unbalanced condition becomes aggravated and, if it is not relieved in some manner, the condenser electrode having the lower capacitance increases to the break-down voltage and produces high losses occasioned by the anode leakage, or sparkling.

One object of my invention, therefore, resides in the provision of apparatus that shall insure satisfactory operating conditions in a condenser which is continuously connected in a power circuit.

Another object of my invention is to provide apparatus, which may be employed in conjunction with an electrolytic condenser to insure good operating characteristics, which shall be relatively inexpensive, simple in construction and easily repaired.

With these and other objects in view, my invention will be more fully described, illustrated in the drawings, in the several views of which corresponding numerals indicate like parts, and then particularly pointed out in the claims.

In the drawings, Fig. 1 is a diagrammatic view of an electrolytic condenser having a

balancing apparatus connected thereto in accordance with my invention, and Fig. 2 is a similar view illustrating a modified form of my invention.

It is desirable, in the employment of electrolytic condensers, that they be of such construction that they may be so connected in an electrical circuit as to insure good operation without the necessity of constant attention. This may be readily appreciated because of the fact that the condensers are frequently located in places where it is inconvenient to have them readily inspected to insure satisfactory operation. In practicing my invention, therefore, I provide apparatus for insuring stable operation of an electrolytic condenser which may be connected in a power circuit and not subject to inspection except at convenient, and perhaps infrequent intervals. I may employ a dynamometer type of relay which is operated by a difference in potential between the main electrodes. The relay automatically connects an auxiliary electrode of relatively low capacitance to one of the main electrodes which is of higher potential than the other to thereby increase the capacitance of the electrode having the higher potential and thereby cause its potential to be reduced to that of the other electrode.

To insure a clear understanding of my invention, I have shown, in Fig. 1, an electrolytic condenser 1 comprising a tank 2 containing an electrolyte 3 in which a plurality of main electrodes 4 and 5 are immersed. The main electrodes 4 and 5 are connected to a secondary winding 6 of a transformer or to a balancing impedance device. I prefer to employ a dynamometer type of relay 7 which comprises a core member 8 having a winding 9 surrounding a portion of the core and connected in series with a non-inductive resistor 9^a and across the supply circuit, or in parallel relation to the secondary winding 6, as indicated at 10 and 11. A rotatable armature member 12 is mounted upon a shaft 13, upon which a contact arm 14 is rigidly mounted and is adapted to engage either of a plurality of contact members 15 and 16 which are connected to the electrodes 4 and 5, respectively. The armature 12 on its shaft 13 is disposed be-

tween the ends of the core member 8. A current coil 17 is wound about the armature 12 and is connected, at one end, through a condenser 18 and a resistor 19, to the mid-point of the secondary winding 6 and, at its other end, to a small electrode 20 which is immersed in the electrolyte 3. An auxiliary film-forming electrode 21, which is preferably of less area than the main electrodes 4 and 5, is connected to the arm 14 mounted upon the shaft 13.

It will be apparent from the foregoing description that the armature 12 is located in a magnetic field which is established, at all times, by the coil 9 of the relay 7. When the voltage between the mid-point of the winding 6 and one of the main electrodes is higher than that between the mid-point of the winding and the other main electrode, a current traverses the current coil 17 from the mid-point of the terminal electrode 20 which causes the armature 12 to be rotated in a direction depending upon the direction of the current through the coil 17. When the armature 12 is rotated, the arm 14 engages one of the contact members 15 and 16 and connects the auxiliary electrode 21 to the main electrode having the higher potential. The condenser 18 is connected in series with the current coil 17 to prevent any flow of direct current through the coil 17, but it permits of free passage of alternating current when unbalanced voltage conditions obtain. On account of the fact that the condenser 18 tends to establish a quadrature current in the coil 17 and, since the coil 9 is essentially a reactance device which also takes quadrature current, it is desirable to connect the resistor 19 in series with the condenser 18 to bring the current in the coil 17 substantially in phase with the potential difference between the electrolyte 3 and the mid-point of the winding 6. The resistor 9^a in the field circuit keeps the current and field flux in the core 8 substantially in time phase with the potential across the electrodes 4 and 5. This insures the component fields of the relay device 7 being in time phase and giving the required torque.

When the total voltage across winding 6 is equally divided between the electrodes 4 and 5, the potential of electrode 20 is the same as that of the midpoint of winding 6 and, therefore, there is no flow of current through coil 17. When the voltage on one of the electrodes 4 or 5 increases, there arises a difference of potential between the electrode 20 and the midpoint of winding 6, the magnitude and direction of which causes a current to flow in the corresponding direction between the said points, thus energizing the coil 17 and moving contactor 14 to add electrode area 21 to either of the main electrodes 4 and 5. After a time the

voltage between electrodes 4 and 5 becomes equalized and the coil 17 is deenergized, causing the contactor 14 to move into its neutral position and disconnecting electrode 21 from the circuit. When the voltage again becomes unbalanced, the cycle is repeated.

It will be appreciated from the foregoing description that any unstable voltage conditions will cause the relay 7 to actuate the lever arm 14 and connect the auxiliary electrode 21 to the main electrode which is having the higher alternating potential impressed thereon. The fluttering relay device will thus keep the voltage balanced by changing the connections of the auxiliary electrode from side to side. The form of relay shown in this instance provides for connection of the total capacity of the auxiliary electrode to the one or the other of the main electrodes when the voltage is sufficiently unbalanced. I may provide a progressive compensation for slight variations in voltage conditions employed a modified form of my invention, as shown in Fig. 2. As here shown, the arm 14 is adapted to engage any one of a series of taps 22 which are connected to various points on the winding 6. An additional condenser 23 is connected between the auxiliary electrode 21 and the arm 14 to prevent the flow of direct current to the auxiliary electrode.

By using a construction, such as shown in Fig. 2, the capacitance of the auxiliary electrode 21 is not immediately connected to one electrode or to the other, as the voltage is varied but is connected to one of the taps 22 on the side of the winding connected to the electrode having the higher voltage. The auxiliary electrode 21 is thus connected to the one or the other of the main electrodes, in a series of steps, by the arm 14 making successive engagement with the various taps 22. Such a construction may be preferable, in some instances, because a more delicate adjustment of voltage balance is maintained.

It will be apparent, from the description of the condensers embodying my invention, that they may be connected in a power circuit and insure satisfactory operation without constant attention because the voltage conditions are maintained in balance and, consequently, the capacitances of the condenser electrodes are maintained at substantially an equal value. Furthermore, the condensers will be longer-lived on account of the fact that stable conditions are maintained. Any corrosive effects on the plates, occasioned by exceptionally high voltages, will be avoided.

Although I have shown and specifically described a plurality of condensers which embody my invention, it is obvious that slight changes may be made in their construction and in the electrical connections

and construction of the relay employed to insure stable operating conditions, and I desire, therefore, that no limitations shall be imposed except such as are indicated in 5 the appended claims.

I claim as my invention:—

1. The combination with an electrolytic condenser comprising a plurality of electrodes immersed in an electrolyte, of means 10 for maintaining the capacitances of the condenser electrodes substantially equal, said means including a switch which is actuated when the voltage is unequally divided between the electrodes.
- 15 2. The combination with an electrolytic condenser comprising a plurality of main electrodes immersed in an electrolyte, of means for maintaining the capacitances of the condenser electrodes substantially equal, said 20 means including an auxiliary electrode and means for connecting the auxiliary electrode to a main electrode when the impressed voltage is unequally divided between the main electrodes.
- 25 3. The combination with an electrolytic condenser comprising a plurality of main electrodes immersed in an electrolyte, of means for maintaining the capacitances of the condenser electrodes substantially equal, said 30 means including an auxiliary electrode of less area than the main electrodes, and means for connecting the auxiliary electrode to a main electrode when the impressed voltage is unequally divided between the main electrodes.
- 35 4. The combination with an electrolytic condenser comprising a plurality of main electrodes and an auxiliary electrode, all immersed in an electrolyte, of means for 40 maintaining the capacitances of the condenser electrodes substantially equal, said means including a plurality of contact members connected to the main electrodes of the condenser, a contact arm connected to the auxiliary electrodes and adapted to engage either of the contact members, and means for actuating the contact arm, said means being governed by the difference of potential impressed upon the electrodes of the 45 condenser.
- 50 5. The combination with an electrolytic condenser comprising a plurality of film-forming electrodes and an auxiliary film-forming electrode of less area than the other electrodes, all immersed in an electrolyte, of means for maintaining the capacitances of the condenser electrodes substantially equal, said means including a plurality of contact members connected to the electrodes, a contact arm adapted to engage the contact members and connected to the auxiliary electrode, a movable supporting member for the contact arm, and means for moving the supporting member to cause the contact arm to 55 engage one of the contact members when
5. The combination with an electrolytic condenser comprising a plurality of main electrodes and an auxiliary electrode of less area than the other electrodes, of means for maintaining the capacitances of the condenser electrodes substantially equal, said means including an impedance device connected to the main electrodes, a plurality of contact members connected to the impedance device, a contact arm adapted to successively engage the contact members and connected to the auxiliary electrode, and means for moving the contact arm to engage the contact members governed by the difference in alternating potential between the midpoint of the impedance device and the electrolyte. 70
6. The combination with an electrolytic condenser comprising a plurality of main electrodes and an auxiliary electrode of less area than the other electrodes, of means for maintaining the capacitances of the condenser electrodes substantially equal, said means including an impedance device connected to the main electrodes, a plurality of contact members connected to the impedance device, a contact arm adapted to successively engage the contact members and connected to the auxiliary electrode, and means for moving the contact arm to engage the contact members governed by the difference in alternating potential between the midpoint of the impedance device and the electrolyte. 75
7. The combination with an electrolytic condenser comprising a plurality of main electrodes and an auxiliary electrode of less area than the other electrodes, of means for maintaining the capacitances of the condenser electrodes substantially equal, said means including an impedance device connected to the main electrodes, a plurality of contact members connected to the impedance device at substantially equally spaced intervals, a contact arm adapted to successively engage the contact members and connected to the auxiliary electrode, a condenser connected in series with the contact arm and the auxiliary electrode, and means for moving the contact arm to successively engage the contact members controlled by the difference in alternating potential between the midpoint of the impedance device and the electrolyte. 80
8. In an electrical power system, an electrolytic condenser comprising a plurality of main electrodes and an auxiliary electrode of less area than the main electrodes all immersed in an electrolyte and having the main electrodes connected to an inductive winding, a plurality of contact members connected to the winding, a contact arm connected to the auxiliary electrode and adapted to make engagement with either of the contact members, a rotatable support for the contact arm, an electrical coil disposed about the rotatable support, means for establishing a magnetic field about the support, and means for causing an alternating current to traverse the coil surrounding the support when the voltage impressed upon the main electrodes is unequally divided therebetween, whereby the contact arm is caused to engage one of the contact members to connect the auxiliary electrode to the main electrode having the higher potential with respect to the electrolyte. 105
9. In testimony whereof, I have hereunto subscribed my name this 23rd day of December, 1919. 110
